(57) **CLAIM**

The ornamental design for a speech processor with hook for a cochlear implant, as shown.

DESCRIPTION

FIG. 1 is a perspective view of a speech processor with hook for a cochlear implant, showing our new design;

FIG. 2 is a front view thereof;

FIG. 3 is a plan view thereof;

FIG. 4 is an inverted plan view thereof;

FIG. 5 is a right side view thereof;

FIG. 6 is a left side view thereof; and,

FIG. 7 is a rear view thereof.
